UNITED STATES PATENT OFFICE.

EDWARD BROOM, OF GLASGOW, SCOTLAND.

PHOTOGRAPHIC ENLARGING APPARATUS.

1,034,968.

Specification of Letters Patent. Patented Aug. 6, 1912.

Application filed May 29, 1911. Serial No. 629,973.

To all whom it may concern:

Be it known that I, EDWARD BROOM, a subject of the King of Great Britain, residing at Glasgow, Scotland, have invented 5 certain new and useful Improved Photographic Enlarging Apparatus, of which the following is a specification.

This invention relates to photographic enlarging apparatus. At present it is usual to 10 make such apparatus with a long and horizontally arranged frame which carries the easel, and the lantern is so arranged relatively to the frame that its light shines horizontally on the condenser and the negative. 15 The result of this arrangement is that a considerable amount of floor space is taken up.

Under my invention I construct the apparatus with a vertically arranged frame and the lantern is also so arranged that its 20 light shines downwardly on to the condenser and the negative. Owing to this vertical arrangement very little floor space is taken up, and, moreover, the parts of the apparatus are so made as to be capable of 25 ready manipulation from one position.

The lantern is carried in such a manner that it can be readily adjusted vertically by means of screw or other gear while the lens is also capable of vertical adjustment by 30 means of screw or other gear.

In carrying out the invention I, preferably, construct the apparatus with a vertical frame for carrying the easel, this frame being open at two sides thereof and also 35 having an opening at the top, and, at opposite sides of this latter opening, and at right angles to the top of the frame I arrange two vertical uprights or supports, one of which serves to support the lantern whose 40 light shines downwardly through the opening at the top of the frame and strikes upon the easel which latter may be fixed in any suitable manner and at any desired point within its frame, the paper to be printed

45 being merely laid upon the easel. The lantern which may be lighted by inverted incandescent gas or other suitable light or lights, has the usual air outlet at the top, the air inlets being provided with a light baffle at 50 three sides thereof and the remaining side having a rectangular guide frame attached thereto. This rectangular guide frame is provided with projections which work in suitable guides fixed on to one of the vertical supports. A screw spindle, rotatably 55 mounted in the top of one of the supports,

engages with a fixed nut provided on the rectangular guide frame carrying the lantern so that, when the spindle is rotated, the nut is raised or lowered thereby raising 60 or lowering the lantern. The lantern is provided, at its lower end, with a frame carrying ground glass, which frame is made removable so that the glass may be readily cleaned. Connected by bellows, and fixed 65 under the lantern, to the two vertical supports, is a box divided by a horizontal partition, the top, bottom and said partition being provided each with a hole or opening so that the light can shine downwardly 70 on to a plano-convex or other suitable condenser carried in the upper portion of the said box, the lower portion of the said box carrying the usual negative frame. Under this box and connected thereto by means of 75 bellows, is a projecting lens frame, at one end of which and at right angles thereto is attached a slide working on a guide, on the second upright support, said projecting lens frame being raised and lowered by means of 80 a screwed spindle, attached to the upper end of the slide, and working in a fixed nut on the box.

The projecting lens is provided with a yellow cap to which is attached one end of a 85 lever fulcrumed on a projection on the lens frame and whose other end is provided with a balance weight or equivalent arrangement so that the cap can be readily held in either 90 its closed or open position.

The invention may also be applied to the ordinary frame for enlarging apparatus, the said frame being placed vertically instead of horizontally, and secured against a wall 95 or partition, or fixed in any suitable manner to the floor or ground. The easel, which is supported by brackets or the like, lies horizontally, and may be fixed at any suitable point on the frame by means of thumb screws or otherwise. The lantern, condenser box, and projecting lens frame are carried by means of two vertical supports 100 which rest on suitable guides provided on a horizontal shelf which projects from the frame. The vertical supports carrying the lantern, condenser box, and projecting lens frame may be moved by hand horizontally 105 along the guideways or by means of screw or other suitable gear, to enable a larger picture to be taken.

In order that my invention may be clearly understood I have hereunto appended ex-

planetary sheets of drawings whereon I have shown, by way of illustration or example, two methods of carrying out my invention.

- 5 Figures 1 to 3 illustrate the preferred form of the apparatus. Fig. 1 is an elevation of the apparatus. Fig. 2 is a section taken on line *a*—*a* of Fig. 3 with the lower portion of the vertical frame 1 removed and 10 Fig. 3 is a plan view of Fig. 1 with the cover of the lantern removed. Figs. 4 to 6 illustrate the invention applied to an ordinary frame for enlarging apparatus, and show means whereby a horizontal movement 15 of the vertical shelves and lantern can be effected. Fig. 4 is an elevation. Fig. 5 is a side elevation partly in section. Fig. 6 is a plan view.

The same reference numerals wherever repeated indicate the same or similar parts.

- 20 Referring to Figs. 1 to 3 of the drawings, I construct the apparatus with a vertically arranged frame 1 provided with series of projections 2 on which the easel 3 rests. 25 The said frame 1 is open at two sides and is provided with an opening 4 at the top thereof, through which two vertical supports 5, 5^a, project, the said supports being supported by means of projecting strips 6, fixed at 30 any suitable part of the vertical shelves 5, 5^a. The lantern 7, which is, preferably, lighted by means of an inverted incandescent mantle 8 to which gas is led by a pipe 7^a, has the usual air outlet 9 at the top, the air inlets 10 provided with a light baffle 11 are located at three sides thereof, the remaining side having a rectangular guide frame 12 attached thereto. This rectangular guide frame 12 is provided with projecting parts 13 which work in suitable guides 14 fixed on to the vertical support 5. A screw spindle 15, rotatably mounted in the top of the support 5, works through a fixed nut 16 provided on the rectangular 45 guide frame 12 which latter carries the lantern 7, so that, when the spindle 15 is rotated, the nut 16 is raised or lowered thereby raising or lowering the lantern. The lantern is provided with a removable cover 17, a sliding door 18, and a frame 19^a carrying ground glass 19 which frame is slidably and removably fitted in the bottom of the lantern, so that the glass may be readily cleaned.

- 50 55 Connected by bellows 20, and fixed under the lantern 7, to the two vertical supports 5, 5^a, is a box 21, divided by a horizontal partition 22, the top, bottom, and said partition, being provided with openings 21^a so that the light can shine downwardly on to a plano-convex or other suitable condenser 23 carried in the upper portion 24 of the box 21, the lower portion 25 of the box 21 carrying the usual negative frame 26. Under the 60 box 21 and connected thereto by means of

bellows 27 is a projecting lens frame 28 at one end of which and at right angles thereto, is attached a slide 29 working on a guide 30 on the second vertical support 5^a, said projecting lens frame 28 being raised and lowered by means of a screwed spindle 31 rotatably attached to the upper end of the slide, and working in a fixed nut 32 on the box 21. The projecting lens 33 is provided with a yellow cap 34 which is attached to 75 one end of a lever 35 fulcrumed on a projection 36 on the lens frame 28 and whose other end is provided with a balance weight 37 so that the cap 34 can be readily held in either its closed or open position. The sensitized paper or plate to be exposed can be simply laid on the easel 3, no fastening devices being necessary. The projections 2 on the frame 1 are spaced so that varying degrees of enlargement can be obtained without special adjustment. Two removable shelves 38 and 39 respectively, resting on the projections 2 of the frame 1, are arranged below the easel 3, and are provided with dishes 40 and 41 in order that the paper or plate may also, if desired, be developed and fixed.

20 Referring to Figs. 3 to 6 of the drawings I apply my invention to the ordinary frame 42 for enlarging apparatus, the said frame 42 being placed vertically instead of horizontally and may be secured against a wall or partition 43 by means of a staple 44 and wedge 45 or other suitable arrangement. The easel 46, which is supported by means of bracket arms 47 or the like, lies horizontally, and may be fixed at any suitable position on the frame 42 by means of thumb screws 48. I provide a suitable horizontal shelf 49 near the top of the frame, this shelf being supported by means of stays 50 or other suitable arrangement, and having an opening 51 which extends to the front of the shelf so as to allow the vertical supports 5, 5^a, to be moved horizontally. The 55 said vertical supports 5, 5^a, rest on suitable guides 52 which are arranged parallel to each other and to the sides of the opening 51.

The lantern 7 is of the same construction as that shown at Figs. 1 to 3 and may be lighted by an inverted incandescent gas mantle. Heat baffle plates 58 are provided on the lantern in order that the woodwork will not be unduly heated. The screw spindle 15 which is rotatably mounted in the bottom of the box 21 extends upward and engages with a fixed nut 16 provided, as before, on the rectangular guide frame which carries the lantern, so that, when the spindle 15 is rotated, the nut 16 is raised or lowered thereby raising or lowering the lantern. Under the box 21 and connected by means of bellows 27 is a projecting lens frame 28 at one end of which and at right angles thereto are arranged two slides 53, 53, working on guides 130

54 on the second vertical support 5^a, said projecting lens frame 28 being raised and lowered by means of a screwed spindle 31 rotatably attached thereto, said spindle 5 working in a fixed nut 32 on the box 21. The vertical supports 5, 5^a, carrying the lantern 7, condenser box 21 and projecting lens frame 28 may be moved horizontally along the guideways 52 by means of a screw 10 spindle 55 rotatably mounted in one end to the frame 42 and extending parallel to the guides 54. A nut 56 fixed to the vertical support 5 engages with the screw spindle 55, so that when it is desired to take a large enlargement, the spindle 55 is rotated so as to cause the vertical supports 5, 5^a, carrying the lantern 7, condenser box 21 and projecting lens frame 28 to be moved outwardly on the shelf 49. Any suitable and well known 20 means may be provided for raising or lowering the light inside the lantern.

Having now fully described my invention, what I claim and desire to secure by Letters Patent is:—

25 1. A vertical photographic enlarging apparatus comprising a lantern the light from which is directed downward, a supporting frame for the lantern, means fitted to the lantern for concentrating the light on the 30 image to be enlarged, means fitted in connection with the lantern for adjusting the same vertically, vertically adjustable means for enlarging the image and horizontal adjustable means on the supporting frame for holding a sensitized surface.

40 2. A vertical photographic enlarging apparatus comprising a lantern the light from which is directed downward, a supporting frame for the lantern, means fitted to the lantern for concentrating the light on the 45 image to be enlarged, means fitted in connection with the lantern for adjusting the same vertically, vertically adjustable means for enlarging the image and internal projections on the supporting frame for holding a sensitized surface.

50 3. A vertical photographic enlarging apparatus comprising a lantern the light from which is directed downward, a supporting frame for the lantern, means fitted to the lantern for concentrating the light on the image to be enlarged, means fitted in connection with the lantern for adjusting the same vertically, vertically adjustable means 55 for enlarging the image, a pivotally arranged balanced cap fitted in connection

with and for the enlarging means and horizontal adjustable means on the supporting frame for holding a sensitized surface.

4. A vertical photographic enlarging apparatus 60 comprising a lantern the light from which is directed downward, a supporting frame for the lantern, means fitted to the lantern for concentrating the light on the image to be enlarged, guides in connection with the frame for the lantern, screw means for adjusting the lantern, internal projections on the supporting frame arranged at varying intervals, removable shelves adapted to be fitted on the external projections for 70 holding a sensitized surface, and means adjustably fitted in connection with the lantern for projecting the image on the sensitized surface.

5. A vertical photographic enlarging apparatus 75 comprising a lantern the light from which is directed downward, a frame for supporting the lantern, a condenser connected with the lantern for concentrating the light on the image to be enlarged, means 80 fitted in connection with the lantern for adjusting the same vertically, a lens adjustably fitted in connection with the lantern for enlarging the image, a pivotally arranged balanced cap fitted in connection with and 85 for the enlarging lens, and means for supporting a sensitized surface below the enlarging lens.

6. A vertical photographic enlarging apparatus 90 comprising a lantern-body, a supporting frame for the lantern-body, a removable cover for the body, a door for the body, an opening in the bottom of the body, a bellows fitted to the bottom of the body, a condenser fitted in connection with the bellows for concentrating the light on the image to be enlarged, a negative frame fitted 95 in connection with said lens, an adjustable lens fitted in connection with the negative frame, guides in connection with the supporting frame for the said body, a guide frame secured to the lantern body and working in conjunction with said guides, means for adjusting the lantern body and means on the supporting frame for supporting a sensitized surface.

In testimony whereof I affix my signature in presence of two witnesses.

EDWARD BROOM.
